UNITED STATES PATENT OFFICE.

RALPH C. BROWNE, OF SALEM, MASSACHUSETTS, ASSIGNOR TO JOHN ABBOTT, TRUSTEE, OF
WINCHESTER, MASSACHUSETTS.

TELEPHONE-TRANSMITTER.

No. 920,424.

Specification of Letters Patent.

Patented May 4, 1909.

Application filed April 26, 1907. Serial No. 370,341.

To all whom it may concern:

Be it known that I, RALPH C. BROWNE, of Salem, in the county of Essex and State of Massachusetts, have invented certain new and useful Improvements in Telephone-Transmitters, of which the following is a specification.

This invention has relation to telephone transmitters of the general character of those illustrated in my application Serial No. 313,578, filed April 25, 1906, in which the current is caused to traverse the resistance or active material transversely of the lines of pressure upon said material. As explained in my said application, by employing a very thin layer of granular carbon or resistance material, I am able to introduce in the subscriber's loop a high resistance, the conductivity of which is easily increased from minimum to maximum to secure the greatest possible variations in current. In my said application, the electrodes are arranged substantially horizontally and care must be taken to maintain them in their proper positions, for if the chamber in the button be not completely filled with the granular material, the dislocation of the button, so as to bring one of the electrodes vertically above the other, will cause it to be out of electrical contact with the carbon.

According to my present invention, I propose to utilize two electrodes, one arranged substantially near the center of the button and the other radially remote therefrom, and provide such a construction and arrangement so that, although the button is rotated about its central axis, nevertheless the electrodes will always be in electrical contact with the resistance material.

Referring to the accompanying drawings,— Figure 1 represents a button or microphone for telephone transmitters embodying my invention. Fig. 2 represents the same with the parts separated, some of the parts being shown in section. Fig. 3 represents a longitudinal section through a transmitter embodying the invention. Figs. 4 and 5 represent another embodiment of the invention. Fig. 6 represents another embodiment of the invention in which the electrodes are provided with points.

Referring to the drawings and more particularly to Fig. 3, a transmitter is shown comprising a cup-like casing *a*, having a cover *a'* with a mouth piece *a''*. The dia-

phragm *b* is supported to receive sound vibrations entering through the mouth piece.

c indicates a solid back consisting of a yoke or bridge, the ends of which are attached to the front wall or cover *a'* of the casing. This bridge or support serves as a solid backing for the microphone or button as ordinarily.

The microphone or button comprises flat retaining walls *d* *d'*. Both of these may be made of mica covered with a silk fabric, although I find it convenient to construct only one of them in that way, as indicated at *d'*. The wall *d* may be fairly rigid and be formed of some suitable insulating material such as hard rubber. These two walls are arranged in parallelism and are separated by annular spacer *e*, being held thereagainst by annular rings *e' e'*, which are internally threaded so as to be screwed upon the spacer *e*.

The members *e e' e'* are formed of metal and they constitute one of the electrodes. When the parts *d d' e e' e'* are secured together, they form a chamber for the reception of the active material which is preferably granular carbon. The layer of active material is very thin although it is exaggerated in the drawings for the sake of illustration. To the front wall *d'* of the button is cemented or otherwise secured a small disk *f* having a boss or pin *f'*, to which the center of the diaphragm is secured by a screw *f''*. To the resilient wall *d'* of the button, which is at the rear thereof, there is attached a metallic disk *g*, having a pin or stud *g'*, which is mounted in an insulating bushing *g'*, located in an annular flange formed in the support *c*. A metallic screw *h* is passed through the wall *d'* into the disk *g* to secure in place an electrode *h'*. This electrode consists of a concavo-convex disk, the edges of which extend into the mass of active material. The inner electrode *h'* is concentric with the outer electrode, and current passes from one to the other in lines transverse to the lines of pressure on the active material.

As the diaphragm is vibrated by the action of sound waves impinging upon it, the granular carbon is compressed, by the movement of one of the retaining walls (that at *d'*) relatively to the other wall (to wit, the flexible wall *d'*). It is evident that the walls may be reversed, and that a diaphragm, separate from the flexible wall, need not be used. For

instance in Figs. 4, 5, and 6, transmitters are shown in which the flexible wall itself is arranged in front and serves as a diaphragm. In these figures *k* indicates the flexible wall 5 or diaphragm, the edges of which are clamped in the casing *a* of the transmitter so that it may receive the sound waves directly upon it through the mouth piece *a*². *m* indicates the rear wall or abutment of insulating material which is backed by the disk *n* of any suitable material. Between the walls or disks *k* and *m* is an annular member, frame, or spacer *o*, to form a thin flat chamber for the layer of variable resistance material. 10 The annular member *o* is made of metal and serves as the outer electrode for the electric current. Attached to the inner face of the rear wall in any suitable way is the central electrode *p* to which is connected a conductor which forms part of the transmitter circuit. The casing *a* which is of metal and which is in contact with the electrode *o* also forms a part of the said transmitter circuit. 15 The electrodes *p* and *o* may be provided with focusing points as shown in Fig. 6.

In the various forms of the invention herein described, there is a thin layer of active material confined between parallel retaining walls of which one is flexible or resilient, and 20 annular electrodes one substantially at the center of the layer, and the other at the outer edge of the layer, said electrodes being substantially concentric.

It is evident that the invention may be 25 embodied in various other forms which will readily suggest themselves to persons skilled in the art.

Having thus explained the nature of the invention and described a way of constructing 30 and using the same, although without attempting to set forth all of the forms in which it may be made, or all of the modes of its use, I declare that what I claim is:—

1. A telephone transmitter comprising 35 parallel retaining walls of which one is movable toward and from the other and the other

is held against movement, a thin layer of active material between said walls and compressed by the relative movement of said walls, and relatively stationary electrodes arranged between the faces of the said layer to permit the passage of current through said active material in paths transverse to the lines of pressure upon said material, one of said electrodes being arranged substantially 50 at the center of said material and the other extending around said first mentioned electrode, said electrodes being separated a distance greater than the thickness of the active material. 55

2. A telephone transmitter comprising a diaphragm to receive sound waves directly thereon, a rear wall parallel thereto, and supported independently thereof, an abutment for the rear wall, a thin layer of active 60 material confined by said diaphragm and said rear wall, and electrodes in electrical contact with said layer between the faces thereof and so arranged that the current between them traverses a path transverse to the lines of pressure of the diaphragm on said material, said electrodes being separated a distance considerably greater than the thickness of the active material.

3. A telephone transmitter comprising a diaphragm adapted to receive sound waves directly thereon, a rear wall parallel thereto, an abutment for the rear wall, a thin layer of active material confined by said diaphragm and said rear wall; a centrally arranged stationary electrode in contact with the said material and a ring-like electrode at the edge of said layer, said electrodes being in the planes of the said layer and being separated a distance greater than the thickness of said 80 active material. 85

In testimony whereof I have affixed my signature, in presence of two witnesses.

RALPH C. BROWNE.
